INVENTOR:
Otto Bernz,
BY
Russell Everett,
ATTORNEY.

UNITED STATES PATENT OFFICE.

OTTO BERNZ, OF NEWARK, NEW JERSEY.

CLEANER FOR BLOW-TORCH NOZZLES AND THE LIKE.

1,343,705.

Specification of Letters Patent. Patented June 15, 1920.

Application filed February 19, 1919. Serial No. 278,065.

To all whom it may concern:

Be it known that I, OTTO BERNZ, a citizen of the United States, and a resident of Newark, in the county of Essex and State of New Jersey, have invented new and useful Improvements in Cleaners for Blow-Torch Nozzles and the like, of which the following is a specification.

This invention relates more especially to cleaners for the nozzle orifices of plumbers' kerosene furnaces, torches and so forth, in which the vaporized hydrocarbon or fuel escapes through an opening a few thousandths of an inch in diameter. This minute opening sometimes becomes clogged, and it has been customary for a long time to clear it with a small piece of wire about a thousandth of an inch smaller in diameter, which can be pushed through the opening. Various devices have been provided for conveniently having such piece of wire accessible, and providing it with a handle or means for applying it to the orifice, but the wire being very fine it breaks off when it is held in such devices and they become useless.

The objects of this invention are to provide means for holding such piece of wire so that it can be used to clear the obstructed orifice of the nozzle, and yet can be carried in the pocket or tool bag or other convenient place when not in use; to obviate inadvertent breakage of the wire, as well as likelihood of it penetrating the clothing or person of the carrier and causing damage or injury; to secure a long handle which will resist downward pressure and at the same time fold up for convenience when not in use; to combine with said folding means for surrounding or inclosing the wire when not in use, to enable the wire to be detached from such holding means and a new one inserted, when desired; to obtain a simple and inexpensive construction, and to secure other advantages and results as may be brought out in the following description.

Referring to the accompanying drawings, in which like numerals of reference indicate the same parts throughout the several views,

Figure 1 is a perspective view of my improved cleaner partially open;

Fig. 2 is a perspective view of the same closed;

Fig. 3 is a side view of the implement;

Fig. 4 is a cross-section of the same on line 4—4, Fig. 3;

55

Fig. 5 is a longitudinal section on line 5—5, Fig. 3, and

Fig. 6 is a detail perspective view of a certain guard for the sheath.

In the specific embodiment of the invention shown in said drawings, 1 indicates the piece of wire to be inserted in the orifice to clean the same, said wire being secured transversely at the end of a holder 2, consisting of a strip of sheet metal, by folding 65 one end of the sheet metal over the wire and clamping it down thereon, as at 3, it being understood that the wire lies transversely of the holder 2 and projects at one side sufficiently to allow insertion to the proper extent in the nozzle orifice.

This holder 2 is pivotally mounted at its end away from the wire 1 in a sheath 4, as by means of a bolt 5, said bolt being readily removable to allow the holder to be replaced 75 by another if the wire becomes broken. It will be understood that a number of such holders, say half a dozen, are supplied with each of my improved sheaths, so that when the wire in one becomes broken it can be 80 thrown away and another inserted.

The sheath 4 I have shown comprising a piece of sheet metal doubled upon a longitudinal central line so as to be U-shaped in cross-section, as shown in Fig. 4, and provide side walls 6, 6 sufficiently spaced to receive the holder 2 between themselves. At the pivotal end of the device, the bolt 5 clamps the side walls 6, 6 and holder 2 close together, and yet not so tightly but that they 90 can be swung with respect to each other. At its opposite end, the sheath provides a guard 7 which is enlarged laterally of the sheath and also extended beyond the back or closed longitudinal edge of the sheath, so that 95 when the holder closes into the sheath the wire 1 will lie in the guard and be surrounded or inclosed thereby. Thus the device, as shown in Fig. 3, can be carried in the pocket or tool bag without any danger 100 of breaking off the fine wire 1, and yet said device is ready for instant use by opening the device as indicated in Fig. 1.

I have shown the guard formed by rounding the side walls 6, 6 of the sheath outwardly apart, as at 8, 8, and then bringing

them together again at their end edges, the connecting back edge of the sheath being cut away. Then a sort of ferrule 9 is inserted between these bowed apart ends of 5 the walls of the sheath, at the back edge of the sheath, and soldered thereto. I have shown the ferrule 9 as bent up out of sheet metal, the radial portions of which have been cut away, as at 10, to allow such bending, although it will be understood that it might be pressed out of sheet metal without such cutting away or might be formed in any other manner common in the art. Furthermore, the said ferrule might be formed 15 integral with the sheath, by a little more complicated stamping process, and I do not wish to be understood as restricting myself to any of these details.

The open edge of the sheath is preferably 20 provided with a recess 11 to provide access to a finger projection 12 at the upper edge of the holder 2, so that the said holder can be opened out of its sheath conveniently, and furthermore I have shown the holder 25 with a recess 13 to receive the lower edge of the door opening in the casing of a conventional plumber's furnace and provide a clearance for the holder 2 to allow the insertion of the cleaning wire 1 into the ori-

fices of the nozzle which is disposed slightly 30 below the said door opening as will be understood by those skilled in the art.

Having thus described the invention, what I claim is:

1. In a device of the character described, 35 the combination of a holder formed of a flat strip of material, a wire projecting laterally from one edge thereof, a sheath for said holder, said sheath having a pair of spaced sides of a width substantially equal to the 40 width of said holder to receive the holder between them, and a guard projecting from one edge of said sheath to receive the said wire on the holder when the holder is arranged between the sides of said sheath. 45

2. In a device of the character described, the combination of a holder formed of a flat strip of material, a wire projecting laterally from one edge thereof, a sheath for said holder, said sheath having a pair of spaced 50 sides of a width substantially equal to the width of said holder to receive the holder between them, and a tubular guard arranged between the sides of said sheath and projecting from one edge thereof to receive the 55 wire when the holder is arranged between the sides of said sheath.

OTTO BERNZ
